CLAIM

We claim the ornamental design for a powered fastener driver, as shown and described.

DESCRIPTION

FIG. 1 is a front perspective view of a powered fastener driver in accordance with another embodiment of the present invention.

FIG. 2 is a left side view of the powered fastener driver of FIG. 1.

FIG. 3 is a right side view of the powered fastener driver of FIG. 1.

FIG. 4 is a front view of the powered fastener driver of FIG. 1.

FIG. 5 is a rear view of the powered fastener driver of FIG. 1.

FIG. 6 is a top view of the powered fastener driver of FIG. 1; and,

FIG. 7 is a bottom view of the powered fastener driver of FIG. 1.

The portions of the powered fastener driver shown in broken lines are included for the purpose of illustrating environment and form no part of the claimed design. The portions of the powered fastener driver shown in broken lines having unequal length segments illustrate the boundary of the claimed design and form no part of the claimed design. The stippling shown on the powered fastener driver in FIGS. 1-4 represents a contrast of materials.
